UNITED STATES PATENT OFFICE.

DUFFY A. MATOT, OF CHICAGO, ILLINOIS.

BEVERAGE-COOLER.

1,366,197.

Specification of Letters Patent. Patented Jan. 18, 1921.

Application filed March 3, 1920. Serial No. 363,032.

To all whom it may concern:

Be it known that I, DUFFY A. MATOT, a citizen of the United States, residing at Chicago, in the county of Cook and State 5 of Illinois, have invented certain new and useful Improvements in Beverage-Coolers, of which the following is a specification.

This invention relates to improvements in that type of cooling devices or refrigerators 10 employed for reducing and maintaining at desired degrees of temperature, beverages of various kinds contained in casks or packages, from which the liquor can be directly drawn and served at such temperature, and 15 it consists in certain peculiarities of the construction, novel arrangement, combination and operation of the various parts thereof as will be hereinafter more fully set forth and specifically claimed.

20 One of the objects of the invention, is to provide a beverage cooler of the above mentioned general character, which shall be simple and inexpensive in construction, strong, durable and highly efficient in operation, 25 with its parts so made and arranged as to provide a combination cooler, of one or more packages containing compartments, and a service counter.

Another object, is to furnish a cooler of 30 such construction of its parts, that, refrigeration of the beverages will thereby be effected while in the packages or casks, thereby eliminating the necessity of coils, which have heretofore been commonly used, besides avoiding the many troubles arising 35 through the use of the same, such as leaks, clogging up and getting slimy and the like, yet permitting the beverage being drawn directly from the package and served at a 40 potable degree of temperature.

A further and important object, is to provide means for facilitating the loading or unloading of the compartment or compartments of the cooler with the packages of 45 beverage, or in other words, for accelerating the handling of packages in placing and properly positioning them in the cooler, or in removing them therefrom.

Still another object is to furnish means 50 for draining the compartments of the coolers and for automatically controlling the amount of ice water contained therein, so as to regulate the temperature of the liquid or beverage.

55 Numerous other objects and advantages

of the invention will be disclosed in the following description and explanation.

In the accompanying drawing, which serves to illustrate an embodiment of the invention—

Figure 1 is a perspective view of a cooler embodying the invention and illustrating by dotted lines about the position a cask or beverage containing package or receptacle will occupy in the initial step of placing it 65 and properly positioning it in one of the compartments of the cooler.

Fig. 2 is a vertical sectional view taken on line 2—2 of Fig. 1, but showing the doors of the compartment closed, and 70

Fig. 3 is a plan sectional view taken on line 3—3 of Fig. 2 as indicated by arrows.

In Fig. 2 I have shown a cooler comprising two spaced apart compartments for the reception of beverage containing casks or 75 packages and interposed therebetween another compartment provided with faucets for drawing off the beverage from the casks, but I desire it to be understood that I do not wish to be limited to any particular 80 number of such compartments or to their aforesaid arrangement, but may use a cooler having one or more of such compartments constructed in the manner and equipped with the improvements as will hereinafter 85 be set forth.

The reference numeral 5 designates as a whole a box-like casing, which by preference is provided at each of its ends with a compartment 6 which extends vertically 90 from the floor to the top 7 of the casing, which top is horizontally disposed as shown, and terminates at one of its side edges about midway between the front and rear walls of the casing. Between the compartment 6 is 95 located what may be termed a service compartment 8 which is preferably equipped with a drip pan or receptacle 9 for holding or catching the drippings from the faucets 10 which are located in one of the walls of 100 said compartment.

The casing 5 is provided in one of its walls, which may be termed the front wall thereof, with a doorway 11 rectangular in construction, which leads to the compartments 6 when more than one of said compartments is employed. The upper edge of the front walls of the casing located at the lower portion of said doorway is inwardly and downwardly beveled as at 12, see Fig. 110

2, and may be located at any suitable distance from the floor of the casing so as to provide means for holding a considerable quantity of water and ice without the same overflowing at the lower edge of the doorway.

Secured to the front wall of the casing by means of hinges 13 is a door 14 for each of the compartments 6 which door has its perimeter formed to correspond with the perimeter of the doorway 11 in order to produce a tight fit when the door is closed.

As a simple and inexpensive way of providing such a closure the perimeters of the doorways and the doors therefor may be correspondingly beveled as shown. Hinged at one of its edges to the front edge of the top 10 of the casing is a door 15 for closing the doorways 16 in the upper portion of the casing, which latter doorways are practically continuations of the doorways 11 in the front wall of the casing. The side walls of each of the compartments 6 are downwardly and forwardly inclined as at 17 so that when the doors 15 are closed, they will occupy forwardly slanting positions as will be readily understood by reference to Fig. 2 of the drawing.

On its inner surface near its top when closed, each of the doors 14 is provided with a horizontally disposed rest bracket 18 which has its inner portion downwardly curved as at 19 to conform to the curvature of the cask or package 20 containing the beverage. Each of said doors has firmly and vertically mounted on its inner surface a strong bar 21 which is provided at its upper end when the door is closed, with an inwardly extended hook 22 and at its other end with an inwardly extended arm 23 which arm is by preference located in an upwardly inclined plane and is considerably longer than the hook 22, as shown in Fig. 2 of the drawing and for the purpose to be presently explained. Each of the bars 21 is of sufficient length to extend considerably below the hinged portion of its door when the latter is closed, and by preference, to near the bottom of the compartment in which it is located.

Now, when it is desired to place a cask or package, which are usually in the form of kegs, in one of the compartments of the cooler, the door 15 of said compartment is elevated and the door 14 thereof is lowered to about the positions shown in Fig. 1 of the drawing, when it is evident that the hooked arm 22 will now be located at the bottom of said door and near the floor, and that the rest bracket 18 for the package will be presented outwardly.

When thus positioned, the cask 20 is placed on the curved portion 19 of the rest bracket and longitudinally on the bar 21, when it is apparent that the hooked arm 22

will engage the chime 23' at the lower end of the keg or package and the arm 23 will engage the other end of the package and will extend inwardly from its chime. In thus placing the package on the door 14 care should be taken to locate the bung 24 of the cask near the hooked end of the arm 22, so that when the door 14 carrying the cask is elevated to the position to close its doorway as shown in Fig. 2 the bung which is eccentrically located in the head of the cask will be positioned in front of the front edge of the top 7 of the casing for easy access thereto and the ready adjustment or application of the liquid draw-off pipe 25 and the pressure pipe 26, which may be applied to the bung and cask in the ordinary or any well known way and which liquid pipe may be connected to one of the faucets 10 while the pressure or air pipe 26 may be connected to a source of air or carbonic gas under pressure not shown.

The pipe 25 is extended at its lower end to very near the bottom of the cask which by reason of the inclination of the supporting arm 23 therefor will be inclined slightly forwardly as shown, so that practically all of the beverage may be withdrawn from the cask. By this arrangement it is also evident that as the liquid is drawn from the lower portion of the cask which is always immersed in cooled or ice water that the beverage may be served at a low or potable degree of temperature until the cask is emptied.

In order to drain the cooler I provide each of the compartments 6 with a drain pipe 27 horizontally located in one of the walls of the casing at the bottom of said compartment, which drain pipe may be provided with a shut-off valve 28 of any suitable kind. Rotatably mounted on the pipe 27 between the valve 28 and the wall of the casing is a coupling 29 from which is extended a trapped overflow pipe 30 by means of which the quantity of water held by the compartment can be automatically regulated and thereby regulating the temperature of the beverage. The pipe 30 being in rotatable communication with the drain pipe 27, can be turned in the proper direction to raise or lower its trapped end 31 so as to regulate the quantity of water held in the compartment as is obvious.

By my improvements it is apparent that the flat top 7 of the casing can be used as a counter on which to rest the glasses in serving the beverages, thus combining a cooler and service counter. It is also manifest that by my improvements ice can be readily placed around the packages or on top of the same and that in the melting thereof the water therefrom will be prevented overflowing at the doorways when the doors are opened or closed.

By my attachments for the lower doors 14 of the cooler it is apparent that the casks can be readily placed and properly positioned within the compartments there- 5 of and can be easily removed therefrom as said doors and their attachments act as levers and holders for the packages, thus relieving the operator of the necessity of lifting the heavy casks bodily above the 10 lower edges of the doorways in placing the packages within the compartments or removing them therefrom.

Having thus fully described my invention, what I claim as new and desire to 15 secure by Letters Patent is—

1. In a device of the class described, the combination with a casing having a water holding compartment therein provided with a vertically elongated doorway termin- 20 nating horizontally at a distance above the bottom of the compartment, of a door hinged at its lower portion to the casing at said horizontal termination of the doorway for vertical movement and closure of 25 said doorway, and a bar longitudinally and fixedly mounted on the inner surface of the door and extended beyond the hinged portion of the door and within said compartment, said bar having means at its ends

for engaging the ends of a package, said 30 engaging means on the lower end of said bar being bodily located in a plane inclined toward said bar for the purpose of retaining the package in a slightly tilted position toward the bar when the door of the 35 compartment is closed.

2. In a device of the class described, the combination with a casing having a water holding compartment therein provided with a vertically elongated doorway terminat- 40 ing horizontally at a distance above the bottom of the compartment, of a door hinged at its lower portion to the casing at said horizontal termination of the doorway for vertical movement and closure of 45 said doorway, a bar longitudinally and fixedly mounted on the inner surface of the door and extended beyond the hinged portion of the door and within said compartment, said bar having at one of its ends 50 an inwardly extended hooked arm and at its other end an inwardly extended arm located bodily in a plane inclined toward said bar for the purpose of retaining a package engaged by said arms in a slightly 55 inclined position toward the bar when the door of the compartment is closed.

DUFFY A. MATOT.
